UNITED STATES PATENT OFFICE.

CLARENCE STONE, OF STROUDSBURG, PENNSYLVANIA.

COTTER-PIN EXTRACTOR.

1,236,016.

Specification of Letters Patent. Patented Aug. 7, 1917.

Application filed September 27, 1916. Serial No. 122,442.

To all whom it may concern:

Be it known that I, CLARENCE STONE, a citizen of the United States, residing at Stroudsburg, in the county of Monroe, State 5 of Pennsylvania, have invented a new and useful Cotter-Pin Extractor; and I do hereby declare the following to be a full, clear, and exact description of the invention, such as will enable others skilled in the art to 10 which it appertains to make and use the same.

This invention relates to a new and useful cotter pin extractor, and an object of the same is to provide a rod member having 15 means to engage the eye of the cotter pin, in combination with an impact member, the latter operating to strike an abutment several hammer blows, in order to extract the cotter pin.

20 In practical fields, the details of construction may necessitate alterations, falling within the scope of what is claimed.

The invention comprises further features and combinations of parts, as hereinafter 25 set forth, shown in the drawings, and claimed.

In the drawings:—

Figure 1 is a view in elevation of a portion of a pulley, showing the same fastened 30 on by a cotter pin and illustrating the extractor connected thereto for removing the pin.

Fig. 2 is a view partly in section and partly in elevation of the extractor.

35 Referring more especially to the drawings, 1 designates a portion of a pulley, which is secured on a suitable shaft 2, by means of a cotter pin 3 passing through the hub 4 of the pulley. Frequently it is very 40 difficult to remove cotter pins, owing to their binding in the openings of a hub of a pulley and the shaft. Hence, it is the purpose of this invention to provide means to overcome this binding action, and extract the 45 cotter pin. This extracting means consists of an elongated steel rod 5 having a hook 6 at one end to engage the eye of the cotter pin when extracting the same. The other end of the rod has an enlargement 7 causing

a shoulder 8 to be formed. This enlargement merges into a tapering blade 8^a, which serves as means for straightening the ends 9 of the cotter pin, in order to render it easier to extract or remove the pin. An impact member 10, which may be of any suitable 50 shape or construction, and constructed from any suitable material, preferably steel, is carried by the elongated rod 5, which telescopes through the longitudinal opening 11 of the impact member. The impact member 55 is loosely mounted upon the rod, and when the hook 6 is in engagement with the eye of the cotter pin, the impact member may be moved or reciprocated several times on the rod very quickly, and impart quick successive impact against the shoulder 8, thereby 60 removing or extracting the cotter pin.

It is obvious that the device may also be used for inserting cotter pins. A cotter pin having once been started in the hole in 70 which it is intended to be inserted, the hook 6 may be made to engage the eye thereof, whereupon the member 10 may be impacted against the cotter pin head to drive the cotter pin in the hole, the hook 6 the while 75 serving to keep the rod 5 connected with the pin and directing the impact member against the head thereof.

The invention having been set forth, what is claimed as new and useful, is:— 80

A cotter pin extractor comprising a rod member having a hook formed at one end for engagement with the eye of a cotter pin and having an abutment formed at the other end, and an impact member through 85 which the rod member passes and which is movable longitudinally from said abutment to the hooked end, whereby a cotter pin may be inserted by successive impacts upon its head or withdrawn by successive impacts 90 against the abutment.

In testimony whereof I have signed my name to this specification in the presence of two subscribing witnesses.

CLARENCE STONE.
